SEAM PRESSING MACHINE

Filed Dec. 20, 1927

2 Sheets-Sheet 2

UNITED STATES PATENT OFFICE.

HARRY WEISNER, OF PHILADELPHIA, PENNSYLVANIA.

SEAM-PRESSING MACHINE.

Application filed December 20, 1927. Serial No. 241,262.

My invention relates to seam pressing machines, especially adapted to the pressing down of the loose edges of seams of garments, which seams are formed by the stitching together of pieces of material such as cloth.

The principal object of my invention is to provide a seam pressing machine of a simple and efficient character, which is particularly adaptable for the pressing of seams of garments and the like, and which may be operated by persons having relatively little skill.

A further object of my invention is to provide a seam pressing machine in which a part of the pressing mechanism is adapted to be maintained in a heated condition to facilitate the pressing operation.

Another object of my invention is to provide a seam pressing machine in which the work may be readily inserted or removed without stopping the machine.

A still further object of my invention is to provide a seam pressing machine comprising a continuously rotating pressing roller, and a retractable idler roller, between which parts the work may be inserted and pressed with a minimum of labor on the part of the operator, and from between which parts the completed work will be removed by the continuing operation of the machine.

The nature and characteristic features of my invention will be more readily understood from the following description taken in connection with the accompanying drawings forming part hereof, in which:

Figure 1 is a front elevational view of a seam pressing machine embodying the main features of my present invention;

Fig. 2 is a vertical sectional view, enlarged, of a portion of the same through the operating parts of the pressing and heating mechanism;

Fig. 3 is a transverse vertical sectional view of a portion of the machine taken approximately on the line 3-3 of Fig. 2;

Fig. 4 is a detail view illustrating the fingers adapted to separate and guide the loose edges of the seams to be pressed;

Fig. 5 is a plan view of a pedal adapted to control the retractable idler roller of the seam pressing device; and

Fig. 6 is an elevational view illustrating a fragmentary detail of the machine.

Referring to the drawings, in the partic-

ular embodiment of my invention therein shown, the pressing device is preferably arranged above a table structure designated 10, which may be of any preferred construction. The same may comprise leg members 11, which may be secured to each other and braced at the top ends thereof, by flat strips 14. The legs 11 may be further braced by flat strips 15, extending between and fastened to the legs a short distance above the floor. A plate 16 is secured to a suitable portion of the framework of the table structure, and serves as a platform or seat for the motor 17 which drives the main pressing roller.

Secured to the framework of the table structure, and extending upwardly therefrom, are bracket members 20, having bearing portions 21 at the upper and outer ends thereof. The constantly rotating pressing roller is journaled in the bearings thus provided, said roller comprising a pressing portion 22 consisting of a ring-like member having a concave working surface 23.

The ring member 23 is recessed as at 24, to provide seats whereby the same may be assembled with respect to cup shaped members 25 and 26. The ring member 22 is also provided with lugs 27, which are adapted to extend into complementary recesses in the cup shaped members 25 and 26 whereby, when the structure of the pressing roller is assembled, the same will be constrained to rotate as a unit.

The cup shaped member 25 is provided with an extending shaft 28, which extends through the bearing portion 21 of one of the brackets 20. The shaft 28 is provided on its outer end with a sprocket 29, adapted to be driven by means of a chain 30, which in turn is driven by a sprocket 31 mounted on the shaft 32 of the motor 17.

The other cup shaped member 26 of the pressing roller structure is provided with a tubular shaft 33, which is mounted in the bearing portion 21 of the other bracket 20. Mounted within the interior of the sleeve-like shaft member 33 is a stationary sleeve 34, which is restrained against rotation by means of an ear portion 35 which is secured by screws 36 to the bearing portion 21 of the bracket 20, through which the sleeve-like shaft 33 extends.

The stationary sleeve 34 serves as a support for a pipe 37 which extends into the chamber formed by the cup shaped mem-

bers 25 and 26, and this pipe 37 is provided on its inner end with a circular burner 38 having outlets directed toward the ring member 22, whereby the pressing roller structure above described may be maintained in a heated condition. The outer end of the pipe 37 is provided with an air mixer 39 of the usual type, and the gas or other fuel used to heat the roller is supplied through a pipe 40,

10 provided with a stop cock 41. Each of the cup shaped members 25 and 26 is provided in its side walls with a plurality of openings 43 for the escape of the products of combustion.

15 There is also provided an idler roller 50, having a convex working surface 51, adapted to engage and coat with the concave working surface 23 of the ring portion 22 of the upper pressing roller, for effecting the pressing operation.

20 The idler roller 50 is journaled by means of a shaft 52 in the upper bifurcated end of a vertical standard 53. The lower end of the vertical standard 53 is movably mounted in a suitable supporting 25 and guiding housing 54, whereby the idler roller is permitted a range of vertical movement to permit the same to contact with the upper pressing roller and also to be retracted therefrom, in the manner to be presently explained. The housing 54 is secured to a suitable portion of the framework of the table structure.

30 The vertical standard 53 is also provided with ears 55. Springs 56 are interposed between the lower surfaces of the ears 55 and suitable portions of the supporting housing 54, which springs 56 normally tend to cause the idler roller 50 to bear toward the upper pressing roller.

35 A pull rod 57 is connected by means of a bolt 58 to eye bolts 59, which in turn are connected to the lower end of the standard 53. The pull rod 57 is adjustably connected by means of a clamping device 60 to another pull rod 61, which is pivotally connected as at 62 to a pedal 63. The pedal 63 is hinged as at 64 to a member 65, which is pivotally connected by means of a screw 66 to the floor, whereby the pedal 63 may not only be depressed, but may also be swung sidewise, this motion being permitted by reason of the pivotal attachment of the member 65. There is also secured to the floor, adjacent a portion of the pedal 63, a bracket member 67, provided 45 with notches 68, into which notches the pedal is adapted to be swung when in the depressed position, thereby to hold the standard 53 in its lowered position, and consequently to hold the idler roller retracted 50 from the upper pressing roller.

55 Mounted on the bearing portion 21 of each bracket 20 is a finger member 70, which is pivotally supported with respect thereto in a bracket 71. The free ends 72 of the finger members 70 are adapted to engage the mate-

rial of the fabric adjacent the stitched portion thereof, to guide the loose edges of the same as the seam passes between the working surfaces of the rollers. Each of the finger members 70 is provided with an upward extension 73, which is engaged by means of a spring 74. In this manner the free ends 72 of the finger members are caused to bear resiliently against the material being operated on, as aforesaid.

60 The table top may be formed of one or more flat pieces of sheet metal 90, in which a suitable opening may be provided for the extension of the standard 53 therethrough. There may also be provided a piece of sheet metal 91 extending upwardly at the rear of the table, to prevent the work from dropping off to the back thereof.

65 The operation of the machine may now be explained. The upper pressing roller, having the concave working surface, and having the heating device mounted therein, is continuously rotated by means of the motor 17, sprocket 31, drive chain 30, and sprocket 29 which is mounted on the shaft 28 extending from the member 25. During the operation of the machine, the burner will usually be lighted, whereby the continuously rotating pressing roller will be maintained in a heated condition.

70 The idler roller 50 being depressed, the material is now placed between the rollers, and the idler roller and its supporting structure released, whereby the idler roller will be caused to bear against one side of the seam, while the other side of the seam will contact with the concave working surface of the ring member 22 of the upper pressing roller. It will, of course, be understood that the finger members 70 will be manually raised to permit the insertion of the material between the rollers. As soon as the idler roller 50 is permitted to bear toward the upper pressing roller, with the material the seam of which is to be pressed interposed between the rollers, the material will now be fed forward, and at the same time the free ends 72 of the finger members 70 will guide the free edges 81 of the fabric 80, spreading the same out so as to enable them to be pressed flat as the fabric passes between the rollers. The action will be continuous so long as the material is fed through the rollers, it being necessary merely for the operator to guide the same toward the free ends of the finger members.

75 It will be found that, in the use of the foregoing machine, seams may be readily and expeditiously pressed, and that the machine is not only adaptable for the pressing of ordinary garment seams, but is also particularly adaptable for pressing the seams of garments such as caps and the like, the pressing of which is more than ordinarily difficult because of their peculiar shape.

80 It should, of course, be understood that I

do not desire to limit myself to the exact details of construction disclosed in the specification and drawings, for various changes and modifications may be made in the construction of the apparatus disclosed without departing from the spirit of my invention.

Having thus described the nature and characteristic features of my invention, what I claim as new and desire to secure by Letters

10 Patent, is:

1. In a seam pressing machine, a pressing roller comprising a ring member having a pressing surface, cup shaped members supporting said ring member, means for constraining said cup members and said ring member to rotate in unison, and the cup members forming a hollow chamber within the roller structure.

2. In a seam pressing machine, a pressing roller comprising a ring member having a pressing surface, cup shaped members supporting said ring member, means for constraining said cup members and said ring member to rotate in unison, the cup members forming a hollow chamber within the roller structure, a burner mounted within said chamber, having outlets directed toward the ring member.

3. In a seam pressing machine, a framework, brackets secured to and extending upwardly from said framework and provided with bearing portions at the upper ends thereof, a pressing roller journaled in said bearings, said pressing roller comprising a ring member having a pressing surface, cup shaped members supporting said ring member, means for constraining said cup members and said ring member to rotate in unison, and the cup members forming a hollow chamber within the roller structure, a burner mounted within said chamber, shafts extending from the cup members through the bearing portions of the bracket, one of said shafts being hollow, a sleeve extending through said hollow shaft provided with means for preventing rotation of said sleeve, and a fuel supply pipe extending through said sleeve to the burner.

4. In a seam pressing machine, a pressing roller comprising a ring member having a concave working surface, cup shaped mem-

bers supporting said ring member, means for constraining said cup members and said ring member to rotate in unison comprising lugs extending from said ring member into complementary recesses in the cup-shaped members, and the cup members forming a hollow chamber within the roller structure, and a burner mounted within said chamber.

5. A seam pressing machine comprising a framework, brackets secured to and extending upwardly from said framework, and provided with bearing portions at the upper ends thereof, a pressing roller journaled in said bearings, said pressing roller comprising a ring member having a concave working surface, cup shaped members supporting said ring member, means for constraining said cup members and said ring member to rotate in unison, and the cup members forming a hollow chamber within the roller structure, a burner mounted within said chamber, shafts extending from the cup members through the bearing portions of the bracket, one of said shafts being hollow, a sleeve extending through said hollow shaft provided with means for preventing rotation of said sleeve, a fuel supply pipe extending through said sleeve to the burner, means for continuously rotating said roller, a movable standard supported from the framework, an idler roller journaled at one end of said standard, said idler roller having a convex working surface, means for causing said idler roller to bear toward the other roller, means for retracting said idler roller comprising a pull rod connected to the standard, a hinged and pivoted pedal having its free end connected to said pull rod, means for holding the idler roller in the retracted position comprising a bracket having notches which said pedal is adapted to engage when the idler roller is in the retracted position, and a pair of spring pressed guide fingers mounted on the bearing portions of the brackets and having their free ends adapted to engage the work as the same passes between the rollers.

In testimony whereof, I have hereunto signed my name.

HARRY WEISNER.
